HOMER R. KENNEDY, OF LOS ANGELES, CALIFORNIA, ASSIGNOR TO GUSSIE M. KENNEDY,
OF LOS ANGELES, CALIFORNIA.

METAL-WORKING TOOL.

1,316,451.

Specification of Letters Patent. Patented Sept. 16, 1919.

Application filed March 29, 1919. Serial No. 286,192.

To all whom it may concern:

Be it known that I, HOMER R. KENNEDY, a citizen of the United States, residing at Los Angeles, in the county of Los Angeles and State of California, have invented new and useful Improvements in Metal-Working Tools, of which the following is a specification.

This invention relates to metal working tools and particularly to tools for removing 10 bumps or indentations in fenders, door panels, tonneaus, cowls, etc., without injury to the enamel.

At the present time whenever a fender or 15 other metal part of an automobile is damaged through collision or other causes, said part is straightened by a process known as hand-peening. This process consists of placing a templet or stake head under the damaged surface of the sheet metal and pounding upon the top surface with a hammer. As will be readily understood, pounding cracks the enamel, and while the surface may be entirely smooth when the job is finished, 20 yet at the same time hand-peening is a long and laborious task. Usually when a fender or other sheet metal part of an automobile is damaged, the fender, door, etc., is removed from the automobile carriage and the 25 work is done in the shop, the result being several hours delay and great expense to the customer. The method of removing bumps or indentations about to be described, consists of a simple arrangement of parts where- 30 by hand-peening is done away with and the indentation may be removed within a minimum of time, and the part or object restored to its original shape usually within 35 five minutes for a bad indentation, at a minimum of expense.

With the above and other objects in view, the invention consists in the novel and useful provision, combination, formation, association and inter-relation of parts, members 40 and features, all as hereinafter described, shown in the drawing, and finally pointed out in claims.

Figure 1 is a side elevation of a sheet metal working device showing a pressure bearing 45 means coöperating with the tongs;

Fig. 2 is a side elevation of roller members in position, the dotted line indicating various positions to which said roller members may be placed in the tong ends;

Fig. 3 is a pressure bar showing swiveled 55 feet thereon;

Fig. 4 is a longitudinal view of a convex surface roller member used in pressing out indentations of sheet metal;

Fig. 5 is a corresponding roller member, 60 but with a concave cylindrical surface;

Fig. 6 is a detail sectional view of a sleeper iron washer and ball-headed tail nut which fits in same;

Fig. 7 is a forked end rod with a link end 65 and pin which join the tongs shown in Fig. 1 together and looking in the direction of the appended arrow;

Fig. 8 is a detail of an approved form of pressure pad;

Fig. 9 is a longitudinal view of a stake head used in the present invention;

Fig. 10 is a lateral view of the stake head shown in Fig. 9;

Fig. 11 is a cross sectional view of the 75 pressure feet used upon the pressure bar illustrated in Fig. 3;

Fig. 12 is an orthogonal view of the serrated portion of the tongs shown in Fig. 1 and looking in the direction of the appended ar- 80 row; and,

Fig. 13 is a fragmentary side view of the T head pressure bolt.

Corresponding parts in all the figures are designated by the same reference characters. 85

Referring with particularity to the drawing, A designates tongs, B a pressure bolt, C a pressure bar, D a roller member, E a corresponding roller member, F pressure feet, G and H stake heads, and J a sleeper 90 iron washer.

Referring to Fig. 1 the tongs A comprise two members *a* and *b*, which are hinge-connected as at 1, one of the members either *a* or *b* having a forked end while the other 95 member is connected to said forked end by a bolt 13. The member *a* has a notched or serrated surface 3 extending longitudinally thereof. The end of the member *a* or that portion farthest removed from the hinged connection between *a* and *b* is mortised as at 4. *b* is correspondingly mortised. The pressure bar B is provided with a flanged T-head *f* as illustrated in Fig. 13 and that portion of the pressure bar farthest removed 100 from the T-head is threaded as at 5. Screwed on this threaded portion is a ball-headed tail nut *c* provided with corresponding

threads. The ball-headed tail nut is provided with a convex portion 6 which fits into a correspondingly concave portion 7 of the sleeper iron washer *j*. The portions 6 and 7 are, as stated, different in size so that a rocking motion may be provided between them. The sleeper iron washer *j* is provided with a bossed head *g* for strength and with flanges 8 which ride upon the surface 10 of the member *b* and act as a guide for the sleeper iron washer *J*. The members *a* and *b* have longitudinal slots *q* so that the T-head pressure bar *B* may move within said slots, as illustrated in Fig. 1.

15 In order to make the device operable the stake heads *G* or *H*, roller members *D* and *E*, as well as the pressure bar *C*, with its walking feet *F* are provided. Each of the members just mentioned are provided with 20 stump tenons 10 shaped as a frustum of a regular pyramid. These tenons 10 fit within the mortise 4 of the members *a* and *b* of the tongs *A* and project in each case from the base of the respective members just mentioned. 25 The purpose of making the tenons in the shape of the frustum of a regular pyramid of any number of sides, shown in the drawing as a tetrahedron, and the mortise 4 of a corresponding shape, is in order that the tenon with its connected member may be forced within the mortise 4 and easily removed therefrom when desired by tapping either of the members *a* or *b* of the tongs *A*. If it were desired to remove 30 an indentation in an automobile fender the pressure bar shown in Fig. 3 would be used on the concave surface of same, while one of the members shown in the remaining figures, as 4, 5, 8 and 9, would also be used 35 on the under surface of the fender. The pressure bar *C* shown in Fig. 3, as mentioned, is provided at its center portion with the tenon 10 and has two arms *d* and *e*, the arms *d* and *e* being conical in shape 40 and the base of the cones being at the part where the tenon 10 joins. This is in order to give strength to the pressure bar and resist compressive stresses. Each of the arms *d* and *e* are provided with flanged portions 45 11 at the end portions of said arms or the part farthest removed from the tenon 10. Upon the conical arms *d* and *e* are placed the swiveled pressure feet *F* as shown in detail in Fig. 11, which feet are convex on 50 their under surface and covered with soft rubber 13. The pressure feet may be of any shape desired, but preferably rectangular. An eyebolt 12 is screwed in the top surface of the pressure feet *F* at a center point, 55 such eye bolt 12 having an inside diameter greater than the diameter of the arms *d* and *e* of the pressure bar *C*.

The roller members illustrated in Figs. 4 and 5 are complementary in formation, one 60 of said rollers being concave while the other

65 roller is correspondingly convex. The roller members 14 and 15 are provided with yokes 16. Connecting the yokes 16 with the roller cylindrical members is an axis 17 held in position to said yokes 16 with cotter pins 70 18 and at the base of the yokes as at 19 are tenons 10, that is, there are two tenons provided at right angles to one another, the purpose being to place the rollers *D* and *E* in the mortise section 4 of the tongs *A* so 75 that the rollers may lie along said tong members or may extend radially downward therefrom as illustrated in Fig. 2.

80 *G* is a form of stake head that may be used in the embodiment of my invention, and *H* is a stake head. Both *G* and *H* may be made in many sections, corresponding to the work to be performed.

85 In operation if it is desired to remove an indentation in an automobile fender, the pressure bar *C* with its swiveled feet *F* would be placed in the mortise 4 of the tong *A* on either of the arms *a* or *b*. On the opposite mortise 4 is placed a stake head *G* or *H*, or if desired one of the roller members 90 *D* or *E*. We will assume for the present that the indentation is very deep; consequently the stake head *G* is placed within the other mortise 4. The flanged pressure bolt *B* is then turned so that the T-head 95 slips through the slotted portion of the member *a*. This allows the tongs *A* to be revolved or adjustably fixed by means of the pivotal connection 1. The pressure bar *C* with its feet *F* are then placed upon the 100 top surface of the fender and the feet are moved along the bars *e* and *d* of the pressure bar *C* to a desired point. The tongs *A* are then closed so that the pressure pad *G* is placed directly under the deepest indentation and the T section of the pressure bolt *B* is slipped through the slot of the member *A* and turned so that the T head comes into contact with the serrated portion 105 3 of the member *a* of the tongs *A*.

110 The sleeper iron washer *J* with its flanges 8 now slips over the edges of the member *b* of the tongs *A*, and the ball-headed tail nut *c* is then rotated so that the pressure is increased by the member *c* screwing radially 115 inward upon the threads 5 of the pressure bolt *B*. The pressure is gradually increased to a certain point and then the ball-headed tail nut *c* is again unscrewed a sufficient distance so that the flange head of the pressure 120 bolt *B* may slip over the serrated portion 3 of the member *a* of the tongs *A*, slipped through the slot and the stake head *G* removed by a slight tapping with a hammer or other means, upon the arm *b* of the tongs 125 *A*. If desired, a roller member *D* may then be placed in the mortise section 4 of the member *b* and the T-headed section of the pressure bolt *B* again slipped through the slot across the serrated portions and the 130

pressure again applied by means of the nut *c*. When this is done, by moving or rocking the tongs *A* up and down a rotatable motion is communicated to the roller *D* and this tends to remove the unevenness from the surface and restore the surface to its original shape.

A method similar to the above consists in placing both roller members *D* and *E* in the mortise 4 of the tongs *A*. When this is used, pressure as above described, is applied and the concave cylindrical surface is usually placed on the convex surface of the auto fender, while the convex roller member *E* is placed upon the concave surface of the auto fender. When pressure is again applied and the T-headed pressure bolt *B* is adjusted in the serrations 3, a reciprocal movement back and forth tends to cause the members 14 and 15 of the roller members *D* and *E* to simultaneously roll the indentation and remove any unevenness completely without injury to the enamel. Obviously many combinations of the roller members and the stake heads may be used, depending, as before mentioned, whether the indentation is on the fender, body, door panel, tonneau, or cowl; however, the exact shape of said members is not an essential feature of the invention.

From the foregoing explanation of the uses of the new tool it will be observed that one of the distinguishing features of the present invention is that the manually operable frame is formed between its arms with a relatively large opening which permits it to straddle the metal body and to be shifted in varying directions to promiscuously located damaged areas of the metal body.

While I have hereinbefore specifically described my invention in its several phases only with reference to the particular embodiments thereof which are illustrated in the drawing, it will be understood that the invention is in principle equally applicable to any sheet metal surface used on any vehicle, and further that it can be variously modified in its various details within the scope of the appended claims, without departing from the spirit or sacrificing the advantages thereof.

Having thus disclosed my invention, I claim and desire to secure by Letters Patent:

1. A tool for removing indentations from sheet metal articles, including a manually-operable frame having a relatively-large opening permitting it to straddle the metal body and to be shifted in varying directions

to the location of a damaged area, opposing shaping elements carried by the frame respectively on opposite sides of the damaged metal area, and pressure applying means carried by the frame.

65

2. A tool for removing indentations from sheet metal articles, including a manually-operable frame having opposing arms adapted to carry complementary and interchangeable shaping elements, said frame also being adapted to straddle the said metal body and to be shifted to promiscuously located damaged areas thereof, means for removably attaching the interchangeable shaping elements, and pressure-applying means.

70

3. A tool for removing indentations from sheet metal articles, including a manually-operable frame, complementary concave and convex shaping rollers fitted to the frame in opposed relation and adapted to be disposed respectively on opposite sides of the damaged part, and pressure applying means.

80

4. A tool for ironing indented sheet metal articles including a manually operable frame carrying opposing ironing elements shaped to permit of rocking and reciprocal movements over the damaged metal part.

85

5. A tool for ironing indented sheet metal articles including a manually operable contractile frame adapted to be placed astride the metal body, oppositely disposed ironing elements carried by the frame and shaped to permit of rocking and reciprocal movements over the damaged metal part, and means for placing said frame under adjustable compression.

90

6. A tool for removing indentations from sheet metal articles, including a manually operable frame formed with pivotally mounted arms which are adapted to span the damaged portion of the sheet metal and are movable toward and away from each other, complementary shaping elements applied to the arms in an opposed relation to each other, and a clamping bolt connecting the arms and adjustable longitudinally into different positions thereon, said clamping bolt providing a means for forcibly swinging the arms toward each other to bring the shaping elements into a proper engagement with the indented portion of the sheet metal article.

100

In testimony whereof, I have signed my name to this specification in the presence of the subscribing witnesses.

HOMER R. KENNEDY.
